Design No. 3,746, dated November 9, 1869.

DESIGN FOR A BRIDLE-BIT.

See Schedule referred to in these Letters Patent and making part of the same

To all whom it may concern:

Be it known that I, JOSEPH B. HOOVER, of the city, county, and State of New York, have invented a new and original Design for Bridle-Bit; and I do hereby declare that the following is a full, clear, and exact description thereof, which will enable others skilled in the art to make and use the same, reference being had to the accompanying drawing, forming part of this specification.

The drawing represents a perspective view of my new bridle-bit.

This invention relates to a new form of side-pieces for bridle-bits.

These side-pieces A A have eyes at the ends, as usual, for receiving the reins, headstall, and straps.

Each side piece A is made in form of a plate, of equal thickness throughout.

The lower arm *a*, which has the eye *b* for the rein-strap, is slightly bent forward, and is less broad between the swell *c* formed for the reception of the bit *B*, and the eye *b*, than at the swell, as shown.

The other arm *d* is somewhat shorter than the arm *a*, and has a broad eye, *e*, flat at the end, as shown.

The back-bar *f*, of the eye *e*, is broader than the opposite bar, in order to receive the aperture *g* for the curb.

I claim, as my invention—

The design for a bridle-bit, as shown.

JOSEPH B. HOOVER.
